US0D1113695S

(12) **United States Design Patent** (10) **Patent No.:** **US D1,113,695 S**
(45) **Date of Patent:** **** Feb. 17, 2026**

(54) **WIRELESS CHARGER**

(71) Applicant: **Shenzhen Yifeng Intelligent Technology Co., Ltd.**, Shenzhen (CN)

(72) Inventor: **Ning Liu**, Shenzhen (CN)

(73) Assignee: **Shenzhen Yifeng Intelligent Technology Co., Ltd.**, Shenzhen (CN)

(**) Term: **15 Years**

(21) Appl. No.: **29/954,948**

(22) Filed: **Jul. 30, 2024**

(30) **Foreign Application Priority Data**

May 12, 2024 (CN) 202430278500.6

(51) **LOC (15) Cl.** **13-02**

(52) **U.S. Cl.**

USPC **D13/108**

(58) **Field of Classification Search**

USPC D13/103, 107, 108, 118, 119; D14/251, D14/252, 253, 447

CPC H02J 7/0044; H02J 7/0045; H02J 7/1423; H02J 9/002

(57) **CLAIM**

The ornamental design for a wireless charger, as shown and described.

DESCRIPTION

FIG. 1 is a front perspective view of a wireless charger of the open state, showing my new design;
FIG. 2 is a rear perspective view thereof of the open state;
FIG. 3 is a front view thereof of the open state;
FIG. 4 is a rear view thereof of the open state;
FIG. 5 is a left side view thereof of the open state;
FIG. 6 is a right side view thereof of the open state;
FIG. 7 is a top view thereof of the open state;
FIG. 8 is a bottom view thereof of the open state;
FIG. 9 is a front perspective view of the closed state;
FIG. 10 is an enlarged detail view of area 10 in FIG. 1.
The broken lines in the drawings illustrate the portions of the wireless charger, which form no part of the claimed design.
The dash-dot-dash broken lines encircling the enlarged views are for annotative purposes only and form no part of the claim thereof.

1 Claim, 10 Drawing Sheets
